UNITED STATES PATENT OFFICE.

CHARLES BASKERVILLE, OF NEW YORK, N. Y.

PROCESS OF REFINING VEGETABLE AND ANIMAL OILS.

1,105,744.

Specification of Letters Patent.

Patented Aug. 4, 1914.

No Drawing.

Application filed February 15, 1913. Serial No. 748,606.

To all whom it may concern:

Be it known that I, CHARLES BASKERVILLE, a citizen of the United States, residing at New York, in the county of New York and State of New York, have invented certain new and useful Improvements in Processes of Refining Vegetable and Animal Oils, of which the following is a specification.

In refining vegetable and animal oils, it is customary to neutralize the free acids present in the crude oil by agitating it with an aqueous solution of an alkali. It is difficult, however, to diffuse the alkaline solution uniformly throughout the oil, while the soaps resulting from the reaction are apt to dissolve in the oil, or form an emulsion therewith, rendering their separation difficult.

According to the present process, the crude oil is agitated for a short period with an organic absorbent impregnated with an alkali, especially with a fibrous vegetable material, such as wood-pulp, unsized paper, fibrous cellulose or cotton, which has been treated with a solution of a caustic alkali or carbonate. The treatment is carried out at atmospheric or low temperatures, and the alkali in the absorbent is brought into intimate contact with and effectively neutralizes the acid contents, the resulting soaps being absorbed by the fibrous carrier. The absorbent also acts to largely decolorize the oil. The process is finished by merely filtering out the absorbent and contained impurities. The cells of the vehicle used as the absorbent present an enormous surface coated with alkaline material, which, owing to its finely divided state, readily combines with the acid present. The water in the vehicle and also in the oil coöperates with the alkaline material in effecting this combination, and in saturating the vehicle with the soap, owing to the surface tension between the wet alkaline cellulose and the soap.

Example: 400 grams of very dark cotton-seed oil, containing 1.85% of free fatty acids, were agitated with about 2 grams of wood-pulp previously treated with a ten-per cent. solution of sodium hydroxid, in amount slightly in excess of that necessary to neutralize the acid in the oil. The agitation was continued for ten minutes in a suitable

mixing apparatus, whereupon the absorbent and contained impurities were filtered out. The product was a light-yellow oil, having an acidity of but 0.14 per cent., suitable for use as a food-product and far superior to a similar oil which had received the customary treatment with soda ash.

The term "saponifiable oils" is used herein to include equivalent substances, such as fats.

I claim:

1. The process of refining saponifiable oils, which consists in treating the oil with an organic absorbent impregnated with a refining agent.

2. The process of refining saponifiable oils, which consists in treating the oil with a fibrous vegetable material impregnated with a refining agent.

3. The process of refining saponifiable oils containing acids, which consists in agitating the oil with a fibrous vegetable material impregnated with an alkali.

4. The process of refining saponifiable oils containing acids, which consists in agitating the oil with a fibrous vegetable material impregnated with an alkali, and filtering out the fibrous material and contained impurities.

5. The process of refining cottonseed oil containing acid, which consists in agitating the oil with a fibrous vegetable material containing an amount of alkali slightly in excess of that required to neutralize the acid, and filtering out the fibrous material and contained impurities.

6. The process of refining saponifiable oils containing acids, which consists in moistening a highly cellular organic vehicle with an alkaline solution, and contacting the moist vehicle with the oil, thereby forming within the cellular vehicle a precipitate of the reaction-product, said precipitate being retained within said vehicle by reason of the surface tension between said moist cellular vehicle and reaction-product.

In testimony whereof I affix my signature in presence of two witnesses.

CHARLES BASKERVILLE.

Witnesses:

THOMAS F. O'KEEFFE,

ALEX F. FRENCH.
